THERMOGRAPHIC METHODS AND PRODUCTS
Douglas A. Newman, Glen Cove, N.Y., assignor to Columbia Ribbon and Carbon Manufacturing Co., Inc.,
Glen Cove, N.Y., a corporation of New York
Filed Sept. 19, 1963, Ser. No. 309,924
9 Claims. (Cl. 101—149.2)

This invention relates to a new and improved method for applying images to a copy or master sheet such as a planographic printing plate by means of an imaged original sheet and infrared radiation, and to the novel master sheets for use in such process.

The planographic printing process is possibly the most popular process in use today for the reproduction of numerous copies of original subject matter. According to such process, the original subject matter is inscribed in the form of images of oleophilic composition on the hydrophilic surface of a planographic printing plate. The plate is then mounted on a printing machine and moistened with oleophilic printing ink which is attracted by the oleophilic images on the hydrophilic printing surface of the plate and repelled by the remainder of the hydrophilic plate surface. The oleophilic ink, in the form of the images, is then transferred indirectly to a series of copy sheets so that one thousand or more duplicate copies of the original subject matter may be formed from the single plate.

It has been proposed that the oleophilic images may be applied directly to a planographic printing plate by means of an imaged original sheet, an oleophilic transfer sheet and infrared radiation. Such a process, as taught for instance by U.S. Patent No. 2,808,777, has met with some success but also involves certain limitations which require that the planographic plate be very translucent or that the sheet bearing the original images be very translucent and have images on only one side thereof. This is so because of the fact that the superposition of the original sheet, transfer sheet and plate requires that the infrared radiation must be unimpeded from being absorbed by the original images which it is desired to duplicate, and the radiation must not be absorbed by any other materials which lie between the original sheet and the plate.

If it is desired to copy an opaque original sheet or one having images on both sides thereof, such as a page from a book, it is necessary that such page be placed at the bottom of the superposed sheets with the images to be duplicated facing up, and to use a translucent planographic plate which will allow the infrared radiation to pass therethrough and be absorbed by the original images. Such translucent plates, based upon parchment paper or plastic film, have been difficult to develop with commercial success in that they present physical problems such as tackiness and curling, do not have sufficient hydrophilic or water resistance properties, and cannot be used as long run plates in that they do not provide more than a few hundred duplicate copies.

A conventional planographic printing plate may be imaged in the known thermographic process but only in such cases where the original sheet is translucent and carries images on only one side thereof. This is so because conventional plates are based upon relatively opaque heavy paper stock having good wet strength properties and do not transmit infrared radiation to any real extent. Most of the radiation appears to be reflected or dissipated by the plate surface and only small amounts of the radiation are absorbed by the plate and/or transmitted thereby depending upon the relative thickness and opacity of the particular plate used. Therefore the use of a conventional plate in the thermographic process

2

is limited to its use on the bottom of the pile of superposed sheets furthest from the radiation source, so that the original sheet must be of a limited nature as indicated.

5 With these problems in mind, it is an object of the present invention to provide a thermographic process for imaging planographic printing plates, using any type of imaged original sheet and using any type of copy sheet.

It is another object of the invention to provide a thermographic process for imaging opaque planographic printing plates using relatively opaque original sheets or original sheets having images on both sides thereof.

These and other objects and advantages of the present invention will be clear to those skilled in the art in 15 the light of the present disclosure, including the accompanying drawing in which:

FIGURE 1 is a diagrammatic cross-section, to an enlarged scale, of a donor sheet, a transfer sheet and an imaged original sheet superposed under the effects of 20 infrared radiation according to the first step of the present method.

FIG. 2 is a diagrammatic cross-section, to an enlarged scale, of the donor sheet imaged according to FIG. 1 superposed with a planographic printing plate under the 25 effects of infrared radiation.

FIG. 3 is a diagrammatic cross-section, to an enlarged scale, of the planographic printing plate imaged according to FIG. 2.

The present objects and advantages are accomplished 30 according to this invention which provides a novel two-step thermographic process which allows for the formation of images on an opaque planographic printing plate, corresponding to images on any type of original sheet, such as an opaque or two-sided original sheet, by thermographic means.

The present process is composed of two separate and distinct steps, the first step comprising the formation of images on a donor sheet directly from an imaged original sheet, a transfer sheet and infrared radiation, and the 40 second step comprising the heat transfer of said images from said donor sheet to the planographic printing plate.

According to the first step of the present method, as illustrated by FIG. 1 of the drawing, an imaged original sheet 30 which is opaque and/or has front infrared radiation-absorbing images 31 and back infrared radiation-absorbing images 32 thereon is superposed with a transfer sheet 20 and a donor sheet 10 so that the original sheet is at the bottom of the pile furthermost from the radiation source 50.

50 The transfer sheet 20 and transfer layer 21 thereon must be free of materials which absorb infrared radiation to any substantial degree so as to permit the radiation to pass through to the original. The transfer sheet must be based upon a translucent foundation such as tissue paper or a clear plastic film such as Mylar or the like.

The transfer layer used according to the present invention is one based upon heat-tackifiable, heat-meltable wax composition including, if desired, small amounts of 60 resinous additives such as Vistanex or Indopol which are isobutylene resins. The preferred wax binders include the relatively soft waxes such as paraffin wax and beeswax. The transfer layer consists of oleophilic wax composition substantially free of pigments or dyes except for the presence of a tint color for proofreading purposes.

The donor sheet 10 must also be translucent and free of materials which absorb infrared radiation to any substantial degree. The donor sheet surface must have good receptivity for the heat-transferable composition of layer 70 21 and yet must freely release said composition to the copy sheet or plate when heated in the second step of

the present process. The donor sheet may be a thin paper such as a tissue paper or a plastic film. In order to provide the best results with respect to receptivity and release properties, however, it is preferred to treat each of these materials. In the case of paper the surface should be coated, calendered or glazed to render it smooth and reduce the "tooth" or ink holding properties thereof. In the case of plastic films it is necessary to coat, etch or frost the surface thereof to increase the "tooth" thereof. It has been found that film-forming coatings, such as of vinyl resins, cellulosic plastics or gelatin or the like hydrophilic colloids, provide the donor sheet or film with a surface having good ink receptive and ink release properties.

In the first step the superposed sheets are exposed to an infrared radiation source, such as lamp 50, which may be conveniently effected in a Thermo-Fax machine. The radiation, applied for a period of a relatively few seconds, is absorbed by original images 31 and causes selective heating thereof. The heat from images 31 is conducted to the oleophilic transfer layer 21 and causes corresponding portions thereof to soften and adhere to the donor sheet 10 so that when the donor and transfer sheets are separated, portions of the transfer layer remain bonded to the donor sheet in the form of oleophilic images 11 which correspond to original images 31.

In the second step of the present process, as illustrated by FIG. 2, the imaged donor sheet is superposed with an infrared radiation-absorbing planographic printing plate 40 so that oleophilic images 11 are in surface contact with the printing surface 41 of the plate, and infrared radiation is applied to heat the plate and soften the images 11 and cause them to bond to the surface of the plate. When the donor sheet and plate are separated, the images 11 remain bonded to the plate surface 41 in the form of oleophilic printing images which correspond exactly to the images 31 of the original sheet, as illustrated by FIG. 3.

In the case of using infrared radiation, such as light source 50, for the step of FIG. 2, it has been found that the duration of exposure to the radiation must be increased to somewhat unpredictable lengths of time because of the varying thickness and opacity of the different plates used unless the plate is treated to render it infrared radiation-absorbing. The plate illustrated in FIGS. 2 and 3 is provided with an infrared radiation-absorbing non-melting back coating or layer 42 which may consist of a black printing ink deposit or a black-pigmented coating or layer based upon plastic bonding agents and containing a substantial amount of pigment which absorbs substantial amounts of infrared radiation. It is also possible that layer 42 be present on the plate as a non-melting undercoating or bonding coating between the hydrophilic printing coating 41 and the plate foundation 40, or that the layer 42 be omitted and such infrared radiation-absorbing pigments be included in substantial amounts in the printing coating 41 to render it infrared radiation-absorbing. In the latter alternatives, it is preferred that the radiation be applied to the plate through the donor sheet 10. The infrared radiation-absorbing layer or coating must be one which does not melt at the temperature generated by the absorbed radiation. Conventional planographic printing coatings based upon hydrophilic colloid binder materials are sufficiently heat-resistant to resist melting at the generated temperatures.

The preferred infrared radiation coatings are those based upon a film-forming binder material and containing at least 10% by weight and up to 90% by weight of any suitable radiation-absorbing pigment such as carbon black, channel black, soot, graphite or the like. Suitable resinous binder materials include vinyl resins such as polyvinyl butyrate, vinyl chloride or vinyl acetate or copolymers thereof, polyvinyl alcohol, acrylate and methacrylate acids and esters, and the like; cellulosic plastics

such as methyl or ethyl cellulose, cellulose acetate, cellulose nitrate, and the like; hydrophilic colloids such as zein, carboxymethyl cellulose, sodium alginate, and the like. In most cases these coatings are applied by means of volatile organic solvents which dissolve the binder material, but in most cases it is preferred to apply them as aqueous solutions or emulsions since the printing coating is also applied in this manner. Preferred binders in this regard are polyvinyl alcohol, methyl cellulose, acrylic and methacrylic resins and the hydrophilic colloids.

In cases where the radiation-absorbing pigment is present in the planographic printing coating, it is preferred to maintain the content low within the range of 10% to 30% by weight of the total weight of the coating although larger amounts may be used depending upon the hydrophilic-oleophilic properties of the pigment and the relative weight thereof. In all cases the amount of pigment must be such that the critical hydrophilic property of the printing coating is not destroyed.

Heat or infrared radiation is applied in the second step for a period of time sufficient to soften the images 11 and cause them to adhere to the plate surface. The use of excessive heat or exposure is to be avoided in that the images tend to melt and flow onto the plate and lose their sharp outlines.

Aside from the possible inclusion of radiation-absorbing materials in the planographic printing coating, such coating consists of any conventional hydrophilic printing coating based, for instance, on carboxymethyl cellulose, sodium alginate, or the like. The planographic coating is also resistant to softening and melting under the effects of the heat generated by the absorbed radiation.

While the process of this invention has greatest application in the field of imaging planographic plates, it should be understood that the present principles apply with equal force to the imaging of hectographic master sheets or single copy sheets, particularly in cases where the master or copy sheets are opaque, reflective or have other properties which prevent their being thermographically imaged directly with an opaque or two-sided original.

Variations and modifications may be made within the scope of the claims and portions of the improvements may be used without others.

I claim:

1. A planographic plate especially adapted to be imaged by means of a heat transfer process, said plate comprising a flexible foundation sheet having on one side thereof a hydrophilic planographic coating and having on the opposite side thereof a second coating containing substantial amounts of infrared radiation-absorbing pigment, said printing coating and said second coating being resistant to softening and melting under the effects of absorbed infrared radiation.

2. The method of forming on a planographic printing plate oleophilic images which correspond exactly to images on an original sheet, which comprises the steps of:

(a) superposing an original sheet having thereon infrared radiation-absorbing original images, a transfer sheet comprising a translucent foundation carrying a layer of heat-transferable oleophilic imaging composition which does not absorb infrared radiation, and a thin translucent paper donor sheet having a smooth treated surface having good receptivity for said heat-transferable imaging composition and having the ability to release said imaging composition to the surface of a planographic plate under the effects of heat, the treated surface of said donor sheet being in surface contact with said imaging composition;

(b) applying infrared radiation to said original images through said donor and transfer sheets for a period of time sufficient to selectively heat said original images and cause corresponding areas of the layer

- of imaging composition to soften and adhere to the treated surface of the donor sheet;
- (c) separating the transfer sheet and donor sheet whereby portions of the imaging composition remain adhered to the donor sheet in the form of oleophilic images corresponding to the original images;
- (d) superposing the imaged donor sheet with a planographic printing plate having a nonmelting infrared radiation-absorbing layer thereon so that the images on the donor sheet are in surface contact with the printing surface of the plate, and applying infrared radiation to said plate to heat the plate and cause said images to soften and adhere to the plate surface; and
- (e) separating the donor sheet and the planographic printing plate whereby the images remain adhered to the plate surface and transfer from the surface of the donor sheet in the form of oleophilic images corresponding to the original images.
3. The method according to claim 2 in which the treated surface of the paper donor sheet comprises a resinous coating.

4. The method according to claim 2 in which the treated surface of the paper donor sheet is calendered.

5. The method according to claim 2 in which the treated surface of the paper donor sheet is glazed.

6. The method according to claim 2 in which the planographic printing plate is one which has a layer of infrared radiation-absorbing material on the surface opposite to the printing surface.

7. The method of forming on a planographic printing plate oleophilic images which correspond exactly to images on an original sheet, which comprises the steps of:

- (a) superposing an original sheet having thereon infrared radiation-absorbing original images, a transfer sheet comprising a translucent foundation carrying a layer of heat-transferable oleophilic imaging composition which does not absorb infrared radiation, and a thin translucent plastic film donor sheet having a treated surface having good receptivity for said heat-transferable imaging composition and having the ability to release said imaging composition to the surface of a planographic plate under the

- effects of heat, the treated surface of said donor sheet being in surface contact with said imaging composition;
- (b) applying infrared radiation to said original images through said donor and transfer sheets for a period of time sufficient to selectively heat said original images and cause corresponding areas of the layer of imaging composition to soften and adhere to the treated surface of the donor sheet;
- (c) separating the transfer sheet and donor sheet whereby portions of the imaging composition remain adhered to the donor sheet in the form of oleophilic images corresponding to the original images;
- (d) superposing the imaged donor sheet with a planographic printing plate having a non-melting infrared radiation-absorbing layer thereon so that the images on the donor sheet are in surface contact with the printing surface of the plate, and applying infrared radiation to said plate to heat the plate and cause said images to soften and adhere to the plate surface; and
- (e) separating the donor sheet and the planographic printing plate whereby the images remain adhered to the plate surface and transfer from the surface of the donor sheet in the form of oleophilic images corresponding to the original images.
8. The method according to claim 7 in which the treated surface of the plastic film comprises a resinous coating.
9. The method according to claim 7 in which the treated surface of the plastic film is etched.
